UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

TESTING DEVICE FOR TELEPHONE-EXCHANGE SYSTEMS.

Application filed May 11, 1923. Serial No. 638,217.

To all whom it may concern:

Be it known that I, WALTER P. ALBERT, a citizen of the United States of America, residing at East Orange, in the county of Essex and State of New Jersey, have invented certain new and useful Improvements in Testing Devices for Telephone-Exchange Systems, of which the following is a full, clear, concise, and exact description.

- 10 This invention relates to a telephone exchange system and more particularly to a testing device for locating faulty selector switches employed in machine switching systems.
- 15 One of the principal requirements in the operation of the telephone exchange system operating either on a manual or mechanical basis is that of maintaining the central office equipment in proper working condition.
- 20 In the case of manual exchanges the central office equipment is relatively simple and the problem of keeping such apparatus in good working order is a comparatively easy one. However, in the case of mechanical offices the
- 25 central office equipment is much more complicated and the establishment of different classes of calls brings into operation, in varying combinations, selector mechanisms of various types, each of which affords opportunities for trouble to arise. The amount of apparatus used in mechanical exchange systems is very large and much of it is made up of moving parts subject to loss of adjustment. All apparatus of this nature, such as relays, interrupters, sequence switches, clutches and selector mechanisms must be watched to detect wear, or broken parts or loss of adjustment which may be a result of normal use of the equipment, or
- 35 the result of mistreatment. Naturally, the failure of any piece of apparatus to function properly will result in the stopping of the progress of calls.
- 40 Such failures ordinarily would not be detected except where calls are repeatedly reported as incomplete, and such service interruptions, if frequent enough, would assume serious proportions from a service standpoint. A fault in a selector switch, causing it to be deterred in its progression when a call is partly completed, will often

cause other apparatus connected to it to remain in an off-normal position. It is highly desirable in tracing troubles of this nature to determine which selectors are connected in cooperative relationship. By this method the position of the sequence switches of the cooperating selector switches can be noted and in the majority of cases the offending element may be quickly discerned and eliminated so that the selector switches can be again placed in service, thus reducing the cost of operation and maintenance of a telephone exchange of this type.

It is the object of this invention to provide a testing device for enabling tests to be made to locate selector switches connected in cooperative relationship on non-completed service connections.

More particularly it is the object of this invention to provide a testing device, to determine which district selector switch is connected in cooperative relationship, with a sender, that has been arrested in its progression.

While the invention has been disclosed as particularly adapted for testing switches of the panel type, it will be however, apparent from the following description that the invention has a wider utility and that, by slight modification, it could be adapted for testing other types of switches.

A feature of the invention relates to the provision of means for locating one of a plurality of district selector switches known to be connected to a sender that has been arrested in its progression.

A further feature of the invention relates to the provision of means to indicate which district selector is connected in cooperative relationship with a sender selector that has been indicated as in trouble.

A further feature of this testing device is in its ability to detect unstandard conditions in a plurality of selector switches at one time with signaling means to indicate the location of the selectors in trouble.

These and other features of the invention will be apparent from the following description taken in connection with the accompanying drawings. Figs. 1, 2 and 3 show portions of apparatus employed in es-

tablishing connections and Fig. 4 the testing device upon which this invention is based. These drawings should be arranged for consideration in accordance with the diagram of Fig. 5.

Fig. 1 shows a district selector of the type completely disclosed in the patent to A. E. Lundell, No. 1,550,377, issued Aug 18, 1925.

Fig. 2 shows a timing device operable from the sender selector switch to indicate after a predetermined time that a sender has remained in a given position longer than necessary to complete its service connection.

Fig. 3 shows diagrammatically such portions of sender as are necessary to an understanding of this invention. A complete sender of this type is disclosed in the patent to A. E. Lundell, hereinbefore referred to.

Fig. 4 shows the testing device. The portion above the dotted line illustrates the mechanism for locating a district that is connected to a sender, that has given a signal indicative that its progression has been arrested. This portion of the testing circuit 25 shows apparatus for a group of 300 districts. There may be several of such groups in an office and therefore the same number of groups of the apparatus shown to the left of the dotted line will be required as there 30 are groups of districts. The apparatus shown below the dotted line is common to any number of such groups.

Description of apparatus.

35 The keys shown in Fig. 4 numbered 493, 494 and 495 are of the non-locking type. The switches controlled by magnets 400, 401, 402 and 227 are of the well known step by step type. The apparatus shown in Figs. 1 40 and 3 is of the same type as that disclosed in the patent of A. E. Lundell hereinbefore referred to.

Having now described in a general way the apparatus employed, it is thought that 45 the utility of this invention will be better understood from a general and detailed description.

General description of utility and operation.

50 In one type of machine switching system the subscriber's line terminates in a line switch responsive to the switchhook of the subscriber's set. The line switch in turn selects an idle district switch which through 55 an associated sender selector becomes connected with an idle sender of the register type. The sender registers are responsive to the impulses transmitted from the dial at the subscriber's station translating these 60 pulses in such a manner that other selector switches are directed to select the called line. If these selections are only partially completed due to an unstandard condition in one 65 of the selector switches, the progressive functioning of the sender will be arrested and

after a predetermined period of time the sender monitor lamp is lighted to indicate this condition.

The district selector switches are divided into large groups and the senders into comparatively small groups. It is therefore readily seen that when an unstandard condition is encountered, when partial selection has taken place, that without the provision of special testing equipment it is difficult to determine which district selector is connected to the sender that has given a signal showing incomplete selections. The testing circuit of this invention has therefore been developed for use in combination with the foregoing circuits, to locate the district selector and give a combination of signals of such nature, that the testing operator will know the location of the district that is connected to the sender flashing the trouble signal.

Each of switches 400, 401, 402, etc., has 100 districts connected to the twenty terminals of five of its bank levels thus enabling each of the switches to test 100 districts to 40 find a district or districts in which unstandard conditions exist. This unstandard condition may exist in either the district selector, associated sender or from apparatus connected thereto as well known in the art. 45

When a district connected to a sender flashing a trouble signal is found by one of the switches of the testing device, the apparatus of the testing device is operated in such manner that one of lamps 488 to 492, inclusive, will be lighted. These lamps indicate in which group of twenty the particular district which is engaged in a deterred connection is located. Also a lamp connected through brush 416, 436, 456, etc., will be 105 lighted to indicate the particular district in a group of twenty and one of lamps 422, 424, 426, etc., will be lighted to indicate the group of one hundred in which the district is located. This combination of lamps will 110 indicate to the test man the exact location of the district selector that is connected to a combination of selectors in which an unstandard condition exists.

Step-by-step switches of a well known 115 type are used in this invention and the combination is such that a plurality of district selectors are tested upon each step of the switch in this testing device.

This testing device may be used to find 120 unstandard conditions in several district selectors at one time, i. e., the testing device may hunt for a district in an unstandard condition and when that is found the testing circuit may again be advanced to hunt for another district in an unstandard condition. More than one district in an unstandard condition may be found when one of the step-by-step testing switches is resting in a 125 single position. This would be indicated by 130

more than one of lamps 488, 489, 490, 491 or 492 being lighted at the same time.

It will be noted that only three of the lamps representing the number within the 5 twenties have been shown connected to the terminals of switches 410, 430, 450, etc., there are, however, twenty lamps connected to the terminals of these switches, the first, ninth and twentieth being shown.

10 *Detailed description.*

Since the functioning of the district selector, Fig. 1 and sender Figs. 2 and 3 in the establishment of regular service connections enters only incidentally into the consideration of this invention reference to the 15 patent of A. E. Lundell, hereinbefore referred to is made for a complete description thereof. This description will, therefore, 20 only cover the operation from a point where a sender and district become arrested in their progression due to trouble from one of various causes known in the art. Selector switches arrested in their progression on 25 account of trouble will be known in this disclosure as unstandard selector switches.

When a sender is taken for use in establishing a connection, a circuit is established 30 for operating the time measuring device shown in Fig. 2 which may be traced from ground through the upper contact of sequence switch spring 311 (1 $\frac{3}{4}$ +18) conductor 234, outer left normal contacts of relay 250, right normal contacts of relay 222, outer 35 right normal contacts of relay 226, conducting segment of interrupter 225, left normal contacts of relay 226, winding of relay 223, to grounded battery, operating relay 223. The operation of relay 223 establishes a locking path for itself through the winding of 40 relay 222 to ground at sequence switch spring 311 over the circuit previously traced, also an operating circuit for relay 222 which is effective when interrupter 225 rotates to interpose an insulated segment in the circuit. The operation of relay 222 establishes a path 45 for operating relay 221. This path, however, is not effective until interrupter 225 has rotated to engage a conducting segment with its brush. The path for operating relay 221 may be traced from ground, through 50 the upper contact of sequence switch spring 311 (1 $\frac{3}{4}$ +18) outer left contacts of relay 250, contacts of relay 223, winding of relay 221, alternate contacts of relay 222, outer 55 right normal contacts of relay 226, conducting segment of interrupter 225, left normal contacts of relay 226, winding of relay 223, to grounded battery. Relay 221 in attracting 60 its right contacts establishes a circuit for operating relay 226 which may be traced from grounded battery through the winding of relay 226, right inner normal contacts of 65 relays 235, right contacts of relay 221, outer left normal contacts of relay 250, upper con-

tact of sequence switch spring 311 (1 $\frac{3}{4}$ +18) to ground. At its left contacts relay 221 establishes a locking path for itself traced from grounded battery through the winding of relay 223, left contacts of relay 221, right alternate contacts of relay 222, winding of relay 221, contacts of relay 223, left outer contacts of relay 250, upper contact of sequence switch spring 311 (1 $\frac{3}{4}$ +18) to ground. Relay 226 in closing its left alternate contacts and outer right alternate contacts, establishes a circuit for operating switch magnet 227 when interrupter 225 engages a conducting segment with its brush. This circuit may be traced from ground connected to terminals of switch bank 260, brush 228, outer right alternate contacts of relay 226, interrupter 225, left alternate contacts of relay 226, left outer normal contacts of relay 235, winding of switch magnet 227 to battery. When interrupter 225 rotates to engage its brush with an insulated segment, magnet 227 will release thus causing the switch 275 controlled thereby to advance one step. As the interrupter 225 continues to rotate, switch 250 will be caused to step from terminal to terminal.

Since the amount of time for the switch 275 to step from the first terminal, to the terminal connected to lamp 219, is in excess 95 of the time that should be occupied by the associated sender in controlling complete connections, the lighting lamp 219 is an indication that an unstandard condition has been encountered. The circuit for lighting lamp 219 may be traced from grounded battery through lamp 219, terminal 10 of bank 261, brush 230, outer right normal contacts of relay 235, interrupter 224, to ground. As interrupter 224 rotates, lamp 219 will be intermittently lighted.

During selections, with sequence switch spring 304 in positions 3+15, a circuit is established for operating relay 310 which may be traced from grounded battery through the winding of relay 310, contacts of sequence switch spring 304 (3+15) normal contacts of relay 305, normal contacts of relay 303, to ground. Relay 310 locks over a path (not shown) and in closing its outer left contacts connects ground to conductor 141 in Fig. 1 over a circuit which may be traced from ground through the outer left contacts of relay 310, left normal contacts of relay 309, left normal contacts of relay 308, conductor 144, switch wiper 143, lower contacts of sequence switch spring 142 (3+10) outer right alternate contacts of relay 121, to conductor 141. A branch of this circuit extends over conductor 445 to a bank terminal of testing switch 400. Similarly a conductor is connected from the terminal banks of the testing device Fig. 4, to each district selector switch.

Lamp 219, associated with each sender,

will indicate the particular sender that has been deterred in its progression, and since this sender is one of a group common to a given group of district selectors, the test man will know the group of district selectors in which to hunt for the district that is associated with such sender.

Key 493 is used to start the testing circuit hunting for a district in one group of one hundred districts and keys 494 and 495 are used as start keys for hunting a district in other groups of districts. Two of these keys cannot, however, be used simultaneously. The description will be confined to the apparatus associated with key 493.

The test man noting the flashing of lamp 219, actuates and releases key 493. The actuation of this key establishes a path for operating relay 499 which may be traced from grounded battery, through the winding of relay 499, lower contacts of key 493, to ground. This relay functions to release any of relays 483 to 487 inclusive that may have been operated from a previous test as will be described hereinafter. The upper contacts of key 493 establish a circuit for operating relay 406, which may be traced from grounded battery, through the winding of relay 406, upper contacts of key 493, inner lower, normal contacts of relay 407, lower normal contacts of relay 408, contacts of relay 480, to ground. The outer lower contacts of relay 406 are not effective at this time. The lower inside contacts of relay 406 establish a locking circuit for itself to the ground at the contacts of relay 480 as traced. This relay also establishes a circuit for lighting lamp 422, traced from grounded battery through resistance 423, lamp 422, contacts of relay 406, thence as previously traced through contacts of relay 480, to ground. At the upper inside contacts of relay 406 a path is established for operating relay 403 which may be traced from grounded battery, through the winding of relay 403, contacts of switch magnet 400, contacts of relay 406, lower normal contacts of key 495, lower normal contacts of key 494, lower normal contacts of key 493 to ground as soon as key 493 is released. The upper outside contacts of relay 406 are ineffective at this time. The operation of relay 403 establishes an obvious circuit for operating switch magnet 400. The operation of switch magnet 400 opens the operating circuit for relay 403 which releases, in turn releasing switch magnet 400 and causing the switch to step one terminal in the manner well known in the art. Switch magnet 400, upon releasing, reestablishes the operating circuit for relay 403, which again reestablishes the operating circuit for switch magnet 400. In this manner magnet 400 intermittently energizes and advances the switch brushes step by step, at each step bringing 5 districts into operative relation-

ship with the testing device until a district is located having a ground connected to lead 141 as hereinbefore described.

Assuming that the district in which the trouble exists, is connected to conductor 445, switch 400 will be rotated approximately half of the arc, where it will stop due to the completion of a circuit for operating relay 484. This circuit may be traced from ground, through the outer contacts of relay 310, contacts of relay 309, contacts of relay 308, conductor 144, brush 143, lower contacts of sequence switch spring 142 (3+10) right outer alternate contacts of relay 121, conductor 445, terminal of switch bank 412, brush 418, contacts of relay 499, winding of relay 484, to grounded battery. Relay 484 in closing its lower inside contacts, establishes a circuit for lighting lamps 489 and 467 which may be traced from grounded battery through lamp 467, terminal 11 of switch bank 410, brush 416, lamp 489, upper contacts of relay 484, lower normal contacts of key 495, lower normal contacts of key 494, lower normal contacts of key 493, to ground. Relay 403 being slow to release, a circuit is established for holding it in an operated position, through the lowermost contacts of relay 484. This circuit may be traced from grounded battery, through the winding of relay 403, upper outside contacts of relay 406, lowermost contacts of relay 484, lower normal contacts of keys 495, 494 and 493, to ground. Relay 403 is now held in an operated position thus maintaining a circuit for holding switch magnet 400 in an operated position, to prevent the switch from stepping further, until the circuit for holding relay 403, has been opened by the operation of key 493.

Lamp 422, which has remained lighted, indicates to the test man that the district is one of the first hundred. Lamp 489, indicates that the district is connected to the terminals of switch bank 412, and is therefore in the second, twenty of the first hundred, and lamp 467 indicates that the district connected is in the second twenty. Therefore, by the lighting of these three lamps, the fact is established that the district in trouble is the 29th district, in the first one hundred districts, in the group of districts under test.

Should the complete rotation of switch 400 not locate a district in trouble this switch would be stopped on terminal No. 1 by ground connected to conductor 446 over a circuit which may be traced from ground, through the lower normal contacts of key 493, lower normal contacts of key 494, lower normal contacts of key 495, conductor 446, brush 417, contacts of relay 499, winding of relay 483, to grounded battery, operating relay 483. Relay 483 in attracting its lower contacts establishes a circuit for holding relay 403 in an operated position,

which path may be traced from grounded battery, through the winding of relay 403, upper outside contacts of relay 406, contacts of relay 483, lower normal contacts of keys 495, 494 and 493, to ground. Relay 403 is held in an operated position and in turn holds switch magnet 400 in an operated position to prevent further stepping of the switch. With switch 400 resting on terminal 10 No. 1 a circuit is established for operating relay 482 which may be traced from grounded battery, through the winding of relay 482, terminal No. 1 of switch bank 410, brush 416, lamp 488, lower inside contacts 15 of relay 483, lower normal contacts of keys 495, 494 and 493, to ground. The operation of relay 482 establishes a circuit for operating relay 407, which may be traced from grounded battery, through the winding of relay 407, lower outside contacts of relay 406, contacts of relay 482, to ground. Relay 407 in closing its lower inside contacts opens the holding path for relay 406 which releases. The release of relay 403 will in turn 20 release relay 403 which in turn releases switch magnet 400, causing the switch to advance one terminal bringing it to rest at its normal position. The release of relay 406 also opens the circuit for lamp 422 25 causing it to be extinguished. The stepping of the switch to normal releases relay 483. Relay 407 in closing its lower inside contacts establishes a locking circuit for itself which may be traced from grounded battery through the winding of relay 407, lower inside contacts of relay 407, lower normal contacts of relay 408, contacts of relay 480, to ground. The closure of the same contacts establishes a circuit for lighting lamp 424 30 which may be traced from the locking ground of relay 407, through lamp 424, resistance 425, to grounded battery. The upper inside contacts of relay 407 establish a circuit for operating relay 404, which may 35 be traced from grounded battery, through the winding of relay 404, contacts of switch magnet 401, upper inside contacts of relay 407, lower normal contacts of keys 495, 494 and 493, to ground. The upper outside contacts of relay 407 are not effective at this 40 time. Relay 404 in attracting its contacts establishes an obvious circuit for operating switch magnet 401. The actuation of switch magnet 401 opens the operating circuit for relay 404 causing it to release which in turn opens the operating circuit for switch magnet 401 causing the switch to advance one step from normal to the first districts of the five groups of twenty in the second hundred 45 of the district group.

Switch magnet 401 upon releasing, establishes the operating circuit for relay 404 which in turn reestablishes the operating circuit for switch magnet 401, which 50 upon operating again opens the operating

circuit for relay 404, releasing it and in turn again releasing switch magnet 401 causing the switch to take a second step to connect the testing circuit with other districts in the group.

70

This switch thereupon continues to step from terminal to terminal in the above described manner until it has found a district in trouble when it will stop in the manner hereinbefore described and light certain of the lamps to show the location of the district selector in the combination of selector switches in which an unstandard condition exists. If an unstandard condition is not located in the second hundred, the switch 75 will rotate to the terminal connected to conductor 447 where it will stop in the manner described for switch 400.

75

Brush 437 connected to conductor 447 establishes a circuit for operating relay 483, 80 which may be traced from grounded battery, through the winding of relay 483, contacts of relay 499, brush 437, conductor 447, lower normal contacts of keys 495, 494 and 493, to ground. The operation of relay 483 establishes a holding circuit for relay 404 which may be traced from grounded battery, through the winding of relay 404, upper outside contacts of relay 407, lower contacts 85 of relay 483, lower normal contacts of keys 495, 494 and 493, to ground. The establishment of this holding circuit for relay 404 will in turn hold switch magnet 401 in an operated position thus preventing the stepping of the switch to the next terminal. Relay 483 in closing its lower inside contacts establishes a circuit for operating relay 481, which may be traced from grounded battery through the winding of relay 481, terminal 1 of switch bank 430, brush 436, lamp 488, 90 inside contacts of relay 483, lower normal contacts of keys 495, 494 and 493, to ground. Relay 481 in closing its contacts establishes a circuit for operating relay 408 which may be traced from grounded battery, through 95 the winding of relay 408, lower outside contacts of relay 407, contacts of relay 481, to ground. Relay 408 in attracting its lower contacts opens the holding circuit of relay 407 causing its release, which in turn causes the 100 release of relay 404, opening the energizing circuit of switch magnet 401 and in turn causing the switch controlled by this switch magnet to advance one step bringing its brushes to rest on the normal terminals of 105 that switch. This switch, in stepping to normal, releases relay 483. The release of relay 407 also extinguishes lamp 424.

100

Relay 408 in closing its lower contacts establishes a locking path for itself which may be traced from grounded battery, through the winding of relay 408, lower contacts of relay 408, contacts of relay 480, to ground. Relay 408 in attracting its upper contacts establishes a circuit for operating 110

115

120

125

130

relay 405 and switch magnet 402, in the same manner as described for the control of switches 401 and 400, rotating this switch to locate a district in the third hundred of 5 the district group in a selector switch combination in which an unstandard condition exists. Should a faulty selector switch be 10 encountered when the switch is rotating over the leads connected to said districts, the switch would be arrested in its progression in the manner previously described for the district located in the first 100 districts tested. If, however, no faulty selector 15 switch is discovered during the rotation of this switch, it will come to the rest on terminal 1 bringing brush 457 into connection with conductor 448 establishing an operating circuit for relay 483, which may be traced from grounded battery, 20 through the winding of relay 483, contacts of relay 499, brush 457, conductor 448, lower normal contacts of keys 495, 494 and 493, to ground. Relay 483 in attracting its lower outside contacts establishes a holding path 25 for relay 405 which may be traced from grounded battery, through the winding of relay 405, upper outside contacts of relay 408, lower contacts of relay 483, lower normal contacts of keys 495, 494 and 493, to ground thus preventing the switch controlled by switch magnet 402 from stepping further at this time.

With this switch brushes resting on terminal 1, a circuit is established for the operation of relay 480 which may be traced from grounded battery, through the winding of relay 480, terminal No. 1 of switch bank 450, brush 456, lamp 488, lower inside contacts of relay 483, lower normal contacts of keys 495, 494 and 493, to ground. The operation of relay 480 opens the locking circuit for relay 408 causing its release and extinguishing of lamp 426. The release of relay 408 in turn causes the release of 40 relay 405 and the release of switch magnet 402 causing it to advance the switch one step into its normal position. The switch in stepping from terminal 1 to its normal position opens the operating circuits for 45 relays 483 and 480 which release.

The testing circuit shown on Fig. 4 now has all of its apparatus in a normal non-operated condition and may again be used for locating faulty selector switch circuits 50 by the depression of one of the start keys 493, 494 or 495.

When the district has been located that is connected to a sender giving the trouble signal, an investigation is made to determine 55 the nature of the trouble. If the district is found to be in standard condition the succeeding selector switches, which are employed in the established connection, over the brushes 154, 157 and 146 of the district and conductors 704, 159 and 720 may be

located and tested. An unstandard condition in any of the selector switches, to which conductors 704, 159 and 720 are extended, would cause the sender Fig. 3, to be deterred in its progression, the same as would an unstandard condition in the district or sender 70 Figs. 1 and 3, respectively.

The patent of Alben E. Lundell, No. 1,550,377, issued Aug. 18, 1925, has been referred to as a basis for portions of this 75 disclosure. To aid in the facility of applying this reference, the numbering of the apparatus for Fig. 1 is the same as that shown in Fig. 2 of the above patent. The apparatus shown in Fig. 3 has been given 80 two sets of numerals. The numerals that are not shown in brackets have been used in this disclosure, and the numerals shown in brackets are those that are shown in the disclosure of the sender in the above mentioned patent.

What is claimed is:

1. In a telephone exchange system, a plurality of selector switches, a sender commonly available to said selector switches, means to associate said senders with one of said selector switches, means to cause said sender to function in a progressive manner to control selector switches, a testing device associated with said selector switches, and means to operate said testing device to locate a selector switch associated with an improperly functioning sender.

2. In a telephone exchange system, a plurality of selector switches, a sender commonly available to said selector switches, means to associate said sender with one of said selector switches, means to cause said sender to function in a progressive manner to control selector switches, a testing device associated with said selector switches, means to operate said testing device to locate a selector switch associated with an improperly functioning sender, and signaling means to indicate the location of the selector switch associated with said improperly functioning sender.

3. In a telephone exchange system, a plurality of selector switches any of which may be in an unstandard condition, a sender commonly available to said selector switches, means to associate said sender with one of said selector switches, means to cause said sender to function in a progressive manner to control said selector switches, said sender being arrested in its progressive operation when associated with an unstandard selector, signaling means responsive to said arrested progression of said sender, a testing device associated with said selector switches, and means to operate said testing device to locate said unstandard selector.

4. In a telephone exchange system, a plurality of selector switches any of which may be in an unstandard condition, a sender com-

- monly available to said selector switches, means to associate said sender with one of said selector switches, means to cause said sender to function in a progressive manner to control said selector switches said sender being arrested in its progressive operation when associated with an unstandard selector, signaling means responsive to said arrested progression of said sender, a testing device 50 associated with said selector switches, means to operate said testing device to locate said unstandard selector, and signaling means to indicate the location of the selector switch in which the unstandard condition exists. 10
5. In a telephone exchange system, a plurality of selector switches, a testing device, means for associating a plurality of said selector switches in operative relation with said testing device at one time, each switch 55 being individually connected to said testing device, and signaling means to indicate simultaneously that certain of said selector switches thus associated are in an unstandard condition. 20
6. In a telephone exchange system, a plurality of selector switches, a testing device, means for associating a plurality of said selector switches in operative relation with said testing device at one time, each switch 60 being individually connected to said testing device, and signaling means to simultaneously indicate the location of any of said selector switches thus associated in which an unstandard condition exists. 25
7. In a telephone exchange system, a plurality of selector switches, a testing device, means whereby said plurality of selector switches may be associated in operative relation with said testing device successively in 65 small groups, each switch being individually connected to said testing device, and signaling means to indicate the location of any of said selector switches in which an unstandard condition exists. 40
8. In a telephone exchange system, a plurality of like combinations of varied selector switches, a testing device, means whereby said plurality of combinations of selector switches may be associated in operative relation 70 with said testing device successively in small groups, each combination being individually connected to said testing device, and signaling means to indicate the location of any of said combination of selector switches in which an unstandard condition exists. 45
9. In a telephone exchange system, a plurality of selector switches, a testing device, means to operate said testing device for 75 making a routine test of said switches, means whereby said plurality of selector switches may be associated in operative relation with said testing device successively in small groups, each switch being individually connected to said testing device, and means to 80
- arrest said testing device when one or more unstandard selector switches of any of said groups are associated with said testing device or in its starting position if no unstandard switches are associated therewith. 70
10. In a telephone exchange system, a plurality of combinations of selector switches, a testing device, means to operate said testing device for making a progressive routine test of said switches, means whereby said plurality of combinations of selector switches may be associated in operative relation with said testing device successively in small groups, each switch of each combination being individually connected to said testing device, and means to arrest said testing device when an unstandard selector is thus associated with said testing device or in its starting position if no unstandard selector is associated therewith. 75
11. In a telephone exchange system, a plurality of selector switches, a testing device, means whereby said plurality of selector switches may be associated in operative relation with said testing device successively in small groups, each switch being individually connected to said testing device, certain of said selector switches being in an unstandard condition, means to arrest said testing device when one or more unstandard selector switches of one of said groups are thus associated with said testing device, and signaling means to indicate the location of each unstandard selector switch. 80
12. In a telephone exchange system, a plurality of combinations of selector switches, a testing device, means whereby said plurality of combinations of selector switches may be associated in operative relation with said testing device successively in small groups, each combination being individually connected to said testing device, means to arrest said testing device when one or more unstandard selector switches is associated with said testing device, and signaling means to indicate the location of each unstandard selector switch. 85
13. In a telephone exchange system, a plurality of selector switches, a sender commonly available to said selector switches, means to associate said sender with one of said selector switches, other selector switches, means to cause said sender to function in a progressive manner to control said switches, said sender being arrested in its progressive operation when associated with an unstandard switch, a testing device, means to operate said testing device to locate the first named selector switch, which is at the time associated with a sender whose progression has become arrested, and signaling means to indicate the location of said first named selector switch. 115
14. In a telephone exchange system, a plurality of selector switches, senders common- 120
- 125
- 130

ly available to said selector switches, means to associate said senders with said selector switches, other selector switches connected in cooperative relation with said first named switches, means to cause said senders to function in a progressive manner to control said switches, said senders or switches being arrested in their progressive operation when unstandard, a testing device, means whereby said first named selective switches may be associated in operative relation with said testing device successively in small groups, and means to arrest said testing device when associated in operative relation with switches in which an unstandard condition exists.

15. In a telephone exchange system, a plurality of selector switches, senders commonly available to said selector switches, means to associate said senders with said selector switches, other selector switches connected in cooperative relation with said first named selector switches, means to cause said senders to function in a progressive manner to control said switches, said senders or switches being arrested in their progressive operation when unstandard, a testing device, means whereby said first named selector switches may be associated in operative relation with said testing device successively in small groups, and signaling means to indicate the location of selector switches that are in an unstandard condition.

20. In an electrical testing system, sets of fixed terminals, a plurality of electrical devices connected to said terminals, brushes, means for advancing said brushes over said terminals, means for arresting said brushes when terminals are encountered to which unstandard devices are connected, and signal-

ing means to denote the location of several 40 of said electrical devices in an unstandard condition in any single position of said brushes.

25. 17. In an electrical testing system, a plurality of electrical devices to be tested, divided into a plurality of groups and sub-groups, a testing device comprising a plurality of hunting switches, one for each group of devices, a plurality of banks of terminals for each of said switches, means for connecting a group of devices by sub-groups to the terminals of the several banks of the respective switch, means for operating said switches in succession to hunt for devices which are in an unstandard condition, means 50 for arresting any of said switches when an electrical device is found to be in an unstandard condition and indicating means associated with the several banks of each of said switches and with the arresting positions of each switch for indicating the groups, sub-groups and particular device in the sub-group in which the unstandard condition exists.

30. 18. A plurality of lines arranged in groups, a switch, a contact bank, for said switch in which said lines terminate, a plurality of brushes for said switch, means to advance said brushes over said contact bank, indicating means associated with certain 55 ones of said brushes to indicate the group locations of a plurality of lines and other indicating means associated with one of said brushes to indicate the locations of said lines 60 within their respective groups.

35. In witness whereof, I hereunto subscribe my name this 10th day of May A. D., 1923.

WALTER P. ALBERT.
